DESIGN FOR A BELT RACK

Sidney Owen, Lincoln, Nebr.

Application February 12, 1940, Serial No. 90,218

Term of patent 3½ years

To all whom it may concern:

Be it known that I, Sidney Owen, a citizen of the United States, residing at Lincoln, in the county of Lancaster and State of Nebraska, have invented a new, original, and ornamental Design for Belt Racks, of which the following is a specification, reference being had to the accompanying drawing, forming part thereof.

Figure 1 is a front elevational view of a belt rack, showing my new design;

Figure 2 is an edge elevational view; and
Figure 3 is a top plan view thereof.

I claim:

The ornamental design for a belt rack, as shown.

SIDNEY OWEN.
